(54) **CUTTING APPLES & PARING/APPLE
PARER**

(76) Inventor: **Moses Coates**

Moses Coates, of Pennsylvania.

Sellers Patent, Sept. 14th 1852.

The schedule referred to in this Sellers Patent and making part of the same, containing a description in the words of the said Moses Coates himself of his improvement, Being a machine for paring Apples, or other fruit.

Specification:

This machine consists of a small board or plank for its basis, and two posts standing erect in which turns a small spindle with a fork at one end to stick the apple, or other fruit, or root on, and a crank at the other end to turn it by, two other studs similar to the former placed to receive and support an arbor which passes through a sweep, from this sweep extends two springs to the tenon which is stocked with wood in such manner as to gauge the thickness of the paring. Stick the apple, fruit, or root on the fork, turn the crank with the right hand, and with the left, move the sweep gradually half round, then the apple, &c, is completely pared. The part for cutting fruit and cores consists of a tube fixed in a box, with wings extending from the verge of the tube, the cores are forced up the tube and conveyed into a vessel placed to receive them by means of ledges on the upper surface of the box, the cut apples fall into a vessel underneath.

Witness,

Asa Brillon,

and Caleb Coates.

Moses Coates.
